[57] CLAIM

The ornamental design for an adjustable lounge chair, as shown and described.

DESCRIPTION

FIG. 1 is a left side elevational view of an adjustable lounge chair showing my new design, the right side being a mirror image thereof;

FIG. 2 is a front elevational view;

FIG. 3 is a top plan view;

FIG. 4 is a rear elevational view; and,

FIG. 5 is a bottom plan view thereof.

The schematic depiction of fabric in FIGS. 2 through 5 is continuous throughout.

FIG. 2.

FIG. 1.

FIG. 1.

FIG. 3.

fig. 5.
